(57) **CLAIM**

The ornamental design for a propeller kite as shown and described.

DESCRIPTION

FIG. 1 is a perspective view of the propeller kite showing my design;

FIG. 2 is an elevated view thereof;

FIG. 3 is a elevated view thereof;

FIG. 4 is a left side view thereof;

FIG. 5 is a right side view thereof;

FIG. 6 is a top view thereof; and,

FIG. 7 is a bottom view thereof.

The broken lines illustrate portions of the propeller kite that form no part of the claimed design.
